FREDRIK LJUNGSTRÖM, OF TUMBA, SWEDEN, ASSIGNOR TO AKTIEBOLAGET SEPARATOR, OF STOCKHOLM, SWEDEN, A COMPANY.

LINER FOR CENTRIFUGAL BOWLS.

No. 892,999.

Specification of Letters Patent.

Patented July 14, 1908.

Application filed January 18, 1905. Serial No. 241,689.

To all whom it may concern:

Be it known that I, FREDRIK LJUNGSTRÖM, a subject of the King of Sweden, residing at Tumba, Sweden, have invented certain new and useful Improvements in Liners for Centrifugal Bowls; and I do hereby declare the following to be a full, clear, and exact description of the invention, such as will enable others skilled in the art to which it applies to make and use the same, reference being had to the accompanying drawings, and to letters or figures of reference marked thereon, which form a part of this specification.

This invention relates to division plates which are used in liners for centrifugal bowls for increasing the capacity of the bowl, and which intersect the radial line of the bowl, thereby dividing the body of the liquid into thin layers. The kind of such liners mostly used consists of superposed conical disks or plates. These plates are generally made with straight mantles or sides. If such conical plates are superposed over each other, the perpendicular distance between the mantles of two adjacent plates is the same at the periphery as at the inner edges of the plates. The smaller the space between the plates the greater the number of plates that can be introduced in the bowl and on this depends directly the skimming capacity of the bowl. If, however, the spaces are made too small, the cream which is of a relatively thick consistency can not pass between the plates with desired velocity, especially on the inner part of the liner and on account hereof it occasions a certain stagnation in these parts of the spaces whereby the skimming capacity is decreased.

It is obvious that the less the top angle of the cone is the greater is the resistance against the cream-flow moving towards the center. The perpendicular space between the conical plates ought therefore to be greater in cases when the top angle is smaller than when the top angle is greater. Plates with straight mantles and great top angle have, however, an inferior skimming capacity to such plates with small top angle. According to this invention the plates are made vaulted or curved in such a way that the inclination towards the axis of the bowl is greatest at the top and smallest at the bottom.

The invention is illustrated in the accom-

panying drawing, which shows a vertical section of a centrifugal bowl with my improved form of plates inserted within.

In said drawing *a* designates the bowl, *b* the cover, *c* the central feed tube and *d* the curved plates having a great angle at the top and a small angle at the bottom.

By means of such plates the advantage is obtained that the decreasing of the skimming capacity which is caused by the great top angle is more than neutralized by the advantageous inclination of the plates at their lower parts.

As the thickness of the plates is the same all over and the decreasing top angle between their mantles has for consequence that the plates require greater and greater space in vertical direction the consequence is that the spaces between the plates decrease proportionately outwards, as shown on the drawing. It is obvious that this fact within certain limits contains no drawback, because the pressure by which the cream is pressed inwardly by means of the skimmed milk increases in proportion to the radial distance from the center-line and at the same time the thickness of the cream-layer passing between the plates is decreased.

If relatively thick plates are used the spaces between them will decrease more rapidly than if thinner plates of the same form are used, for instance, if plates of 1 mm. thickness are used, the decrease of the space between the plates becomes twice as great as if the plates are only one-half mm. thick. It is thus possible by using thin plates to give the same a smaller and for the skimming capacity more advantageous angle at the outer edges without decreasing the spaces between them or the practical limit. For this reason it is advantageous to make the plates of the above mentioned shape very thin, as thereby a considerably greater number of plates can be introduced into a bowl of fixed height and furthermore the skimming capacity of each plate will be increased.

I claim as my invention:

1. A liner for centrifugal liquid separators consisting of a series of superimposed separating plates extending from near the axis of the bowl toward the periphery and forming passages between adjacent plates, there being a passage between the outer end of the plates and the wall of the bowl into which the passages between the plates open, each

plate being so formed that the width of the spaces between it and its adjacent plates is less at the outer than at the inner ends of said spaces.

5. 2. A liner for centrifugal liquid separators consisting of a series of superimposed curved separating plates, extending from near the axis of the bowl toward the periphery and forming passages between adjacent plates, 10 there being a passage between the outer end of the plates and the wall of the bowl into which the passages between the plates open, each plate being so formed that the width of the spaces between it and its adjacent plates 15 is less at the outer than at the inner ends of said spaces.

3. A liner for centrifugal liquid separators consisting of a series of superimposed converging separating plates, extending from 20 near the axis of the bowl toward the periphery and forming passages between adjacent plates, there being a passage between the outer ends of the plates and the wall of the bowl, and into which the passages between 25 the plates open, each plate being so formed that the width of the spaces between it and its adjacent plates is less at the outer than at the inner ends of said spaces.

4. A liner for centrifugal liquid separators 30 consisting of a series of superimposed separating plates extending from near the axis of the bowl toward the periphery and forming passages between adjacent plates, there being a passage between the outer end of the 35 plates and the wall of the bowl into which the passages between the plates open, each plate being so formed that the width of the spaces between it and its adjacent plates is gradually narrowed from the inner ends of 40 said spaces outward.

5. A liner for centrifugal liquid separators consisting of a series of superimposed curved separating plates, extending from near the axis of the bowl toward the periphery and 45 forming passages between adjacent plates, there being a passage between the outer end of the plates and the wall of the bowl into which the passages between the plates open, each plate being so formed that the width of

the spaces between it and its adjacent plates 50 is gradually narrowed from the inner end of said spaces outward.

6. A liner for centrifugal liquid separators consisting of a series of superimposed converging separating plates, extending from 55 near the axis of the bowl toward the periphery and forming passages between adjacent plates, there being a passage between the outer end of the plates and the wall of the bowl, and into which the passages between 60 the plates open, each plate being so formed that the width of the spaces between it and its adjacent plates is gradually narrowed from the inner ends of said spaces outward.

7. A liner for centrifugal liquid separators 65 consisting of a series of superimposed curved separating plates, having their mantles of the same thickness throughout and extending from near the axis of the bowl toward the periphery and forming passages between adjacent plates, there being a passage between 70 the outer end of the plates and the wall of the bowl into which the passages between the plates open, each plate being so formed that the width of the spaces between it and its adjacent plates is gradually narrowed from the inner ends of 75 said spaces outward.

8. A liner for centrifugal liquid separators consisting of a series of superimposed curved separating plates, having their mantles of 80 the same thickness throughout and extending from near the axis of the bowl toward the periphery and forming passages between adjacent plates, there being a passage between the outer end of the plates and the wall of the 85 bowl into which the passages between the plates open, all the curved plates being of the same shape so that the width of the spaces between them on account of their curvature may be gradually narrowed from the inner 90 end of said spaces outward.

In testimony, that I claim the foregoing as my invention, I have signed my name in presence of two subscribing witnesses.

FREDRIK LJUNGSTRÖM.
